CLAIM

The ornamental design for a water display device, as shown and described.

DESCRIPTION

FIG. 1 is a front view of the display device installed within a wall and an adjacent archway with the wall and archway depicted in phantom and forming no part of the claimed design; therefore, a portion of the display device is concealed.

FIG. 2 is a perspective view of the display device.

FIG. 3 is a front view of the display device.

FIG. 4 is a left side view of the display device.

FIG. 5 is a right view of the display device.

FIG. 6 is a top view of the display device; and,

FIG. 7 is a bottom view of the display device.
